COLLAPSIBLE EASEL

Harry V. Marsh, Chicago, Ill.

Application March 28, 1931. Serial No. 526,049

3 Claims. (Cl. 40—146)

This invention relates to improvements in advertising display placards and in particular to a collapsible display standard having means for rigidly supporting thin paper advertising material.

Fastening paper sheets having advertising material thereon to a framework composed of cheap light material so as to present a taut and neat appearance as contrasted with a flabby, ruffled appearance has been a difficulty encountered in bulk production.

Unless frameworks have been composed of heavy material, many previous devices have failed because the paper displaying the printed material has hung irregularly or in folds and presents an unattractive appearance, the very thing which a successful advertisement must avoid. The defect just described is more common in frameworks which are collapsible. Such easels have joints which work loose and the devices have heretofore quickly become unsatisfactory.

The first object of the present invention is to provide a cardboard framework or easel upon which may be hung paper advertisements which are held tautly in a predetermined position and not permitted to hang in wrinkles or folds or to flap loosely about.

A second object of the invention is to make such a cardboard frame of the most ordinary cardboard material, so fastened together that the easel may be taken down into a series of strips of uniform width but of irregular length. Such strips when taken down provide a compact, collapsed package designed so that it may be wrapped in the paper carrying the advertising material and kept in this form until the advertisement is actually erected.

An unique object of the present device is to so combine a sheet of thin paper and the framework that an intermediate strip or frame member will maintain the paper taut and a single supporting strut will hold the standard upright. Heretofore it has been customary to have at least two frame members and two struts to obtain lateral as well as transverse support.

In order to assure tautness of the paper advertisement, an expansion means is inserted between the upper and lower spars (fastened to the upper and lower edges of the paper) and the upright stud. An expansion force is exerted upon the spars which stretch the paper transversely and longitudinally. Such result is accomplished by the use of flexible means intermediate one spar and an upright member or between component parts of the member itself.

The invention assumes various forms and there are many unique arrangements whereby a single cardboard strip may serve several purposes, thereby reducing to a minimum undesirable rivets and punch holes.

The objects hereinabove recited and such other objects as may hereinafter appear are obtained by the unique construction and combination of the parts to be described.

In the accompanying drawings:

Figure 1 is an elevation of an erected placard as seen from the rear embodying one form of the invention;

Figure 2 is a longitudinal section of the device shown in Figure 1 adjacent its middle point;

Figure 3 is an enlarged detail view of the expansion device in the head of the upright stud;

Figure 4 is a fragmentary elevation of the central upright portion of another adaptation of the invention;

Figure 5 is a longitudinal section of the device shown in Figure 4 at its median point;

Figure 6 is a fragmentary elevation of a portion of a third form of the invention as seen from the rear;

Figure 7 is a longitudinal section of the device shown in Figure 6 at its median point;

Figure 8 is an enlarged detail of an elastic means intermediate the component parts of the upright portions of the easel shown in Figures 6 and 7;

Figure 9 is a rear elevation of another form of the invention wherein expansion is obtained by elements arranged in a Y shape;

Figure 10 is a longitudinal section of the device shown in Figure 9 at its median point;

Figure 11 is a rear elevation of a device where a fifth type of stretching means is employed;

Figure 12 is a longitudinal section of the device shown in Figure 11 at its median point;

Figure 13 is a rear elevation of a device having two Y-shaped expansion means to hold the paper front in stretched condition;

Figure 14 is a longitudinal section of the device shown in Figure 13 at its median point;

Figure 15 is a rear elevation of another form of the invention wherein a different type of Y-shaped expansion means is used;

Figure 16 is a longitudinal section of the device shown in Figure 15 taken at its median point; and

Figure 17 is an elevation of any of the devices hereinabove mentioned when collapsed in a form suitable for packaging or packing.

nate similar parts in the drawings and in the description of the invention which follows.

The present invention may assume so many slightly different forms that it is thought desirable to describe each of the foregoing in some detail.

In Figure 1, the numeral 10 represents a sheet of paper or other material which may be rolled. Upon the outward surface of such sheet advertising matter is printed. The numeral 11 represents a cross spar of heavy material, usually cheap cardboard, fastened at 12 to the sheet material 10 by suitable adhesive such as glue or paste. The numeral 13 represents an upper 15 spar similarly fastened to the sheet material by adhesive 14.

The device, before erection, is generally in a collapsed form with the sheet 10 wrapped about the easel parts. When spread out, there are generally folds in the sheet material 10 due to the previous folding. These present an irregular surface to the eye particularly upon a printed calendered surface and the problem is to spread apart the spars 11 and 13 so as to draw sheet material 10 tautly between the two spars. This may be accomplished by an easel 14 which, as may be seen in Figure 2, is composed of two strips 15 and 16 with overlapping ends which are joined at an apertured point 17 by means of rivet 18 passing 30 through said apertures.

In order that the easel may be readily attached to and removed from reinforcing strips 11 and 13, to which the easel is attached when the device is in use, strip 16 is provided with an inverted keyhole slot 20 in its upper portion. Cross members 11 and 13 are fastened to their respective ends of easel 14 by the use of rivets 21 and the shanks of which fit into keyhole slots 19 and 20.

40 By means of a strip 27 fastened to easel 14 by rivet 18 and held in fixed relationship to easel 14 by strip 28 bent at 29 to form an extension engaging said strip 27 by the employment of a T-shaped tongue 30 extending through a T-shaped slot 31, vertical positioning of the easel is assured.

The sheet and easel would not stand rigidly, however, unless easel 14 is exactly measured to distend sheet 10 its full length. Advertising devices of this kind are saleable only when very cheap. They are therefore made in mass production. The result of machine, mass production is that there may be variations in said sheet material and the position of strips 11 and 13 thereon. Due to the same mass production of easels 14, there may be variations in the positioning of keyhole slots 19 and 20 and of the rivet 18. The result is that the advertising sheet or poster often is inclined to flabbiness and wrinkling when erected.

60 In order to eliminate these defects, a simple expansion device has been provided. In the present form of the invention, it is placed between the upper part of the easel 14 and cross strip 13. As may be seen in Figure 3, the slot in keyhole 20 in strip 15 is elongated, the narrow part being marked 21. The shank 26 of rivet 25 may freely move up and down in section 70 21.

Oppositely disposed adjacent the top of strip 15 of easel 14 are notches 32. In the end of said strip 15 is a notch 33. By placing an elastic band or cord 34 over rivet 25 and between strip 15 and strip 13 before inserting the rivet 25 through the

slot 32 and subsequently drawing the intermediate sections of said elastic outwardly so as to engage in said several notches, as shown in Figures 2 and 3, the elastic 34 will be run upwardly over notch 33 and hooked over the shank of rivet 25. The opposed end of said elastic 34 will extend across the inside of the easel from notch 32 to second notch 32, forwardly, and upwardly over the slot 33.

80 By use of the elastic, inaccuracies in the cutting of sheet material 10 and attaching the cross members 11 and 13 thereto, as well as the inaccuracies of the easel 14 may be compensated. The extent of the elongated slot 21 in keyhole 20 permits of rivet 25 riding therein in a position to provide stretching of the sheet 10. The rubber band 34, using notch 33 as a base, draws rivet 25 and cross member 13 upwardly until the sheet material 10, by even stretching thereacross prevents further movement.

90 The easel is compact when collapsed. Strip 15 of easel 14 is disengaged from strip 13 and is then swung 180 degrees or entirely removed. T-tongue 30 is disengaged from T-slot 31. The result is that four parallel strips which may be of varying lengths are made parallel in a compact package. The strips may be laid along one strip (11 or 13) and the whole device rolled into a compact bundle (see Figure 17).

95 In Figure 4 there is a similar sheet 10 and cross members 11 and 13 and an easel 114 attached to rivets 21 and 25 by keyhole slot 20 and inverted keyhole slot 19 therein. Easel 114 is composed of strips 35 and 36 which are held together to form an elongated easel in a different manner 100 from that previously described.

105 Said easel 114 receives backward support from a strip 37 which is bent into a triangular shape at scores 38 and 39 and held in such shape by a T-tongue 40 extending through a T-shaped slot 41. One side of the triangular strip 37 is fastened to easel 114 at any suitable points by rivets 42.

110 Strips 35 and 36 overlap and have in the edges of their overlapping sections outwardly disposed, 115 staggered notches 43 which are so positioned that by winding an elastic 34 diagonally across said notches, a force may be imparted to said members 35 and 36 to move them longitudinally to attain greater length, which force is applied to rivets 21 and 25 in strips 11 and 13, thereby drawing taut the sheet material 10.

120 By disengaging the T-tongue 40 from the T-shaped slot 41, and detaching strips 35 and 36 from spars 25 and 21, the several strips may be 125 arranged in parallelism to provide a compact bundle.

130 A third form of the invention is illustrated in Figures 6, 7 and 8. Such form of the invention presents the same fundamental features as described in the last described form of such invention.

135 The details of the changes include the replacement of the lower keyhole slot 19 in Figures 1 and 4 by an ordinary round hole so that rivet 21 and its head 23 permanently fasten the leg 14 forming strip 44 to lower strip 11. Such permanent fastening is possible because on collapsing said easel 214, strip 44 may be angularly moved with rivet 21 as an axis and thereafter rolled up within the sheet material 10.

140 In this, the third form of the invention, the expansion or stretching means is again intermediate the vertically extending strips 44 and 45 which form the easel 214. As may be seen in Figure 8, there is cut in the lower part of strip 45

a slot 46, which runs longitudinally of strip 45. Slot 46 is made to register with a hole 47 in strip 44 and rivet 48 is inserted through said aperture and slot thereby holding strips 44 and 45 together. It will be noticed that strip 44 forms a section of the leg forming strip mentioned in previous forms of the device; that is, strip 44 is part of a continuous strip having a section 51 and terminating with a T-tongue 52 locking in 10 T-shaped slot 53 in section 51.

In the surface of said strip 44 at articulation 54 therein is a rectangular slot 55. A continuous elastic band 134 is hooked upon the shank of the rivet 48 and extends upwardly through the 15 rectangular slot 55, over the upper end of strip 44, and through the slot 46 to hook upon notches 56 in the lower edge of strip 45.

The elastic 134 employs the upper end of strip 44 as a support to and applies a pull exerted at 20 notches 56 upon the strip 45, to force the strips 11 and 13 on sheet 10 apart until sheet material 10 is drawn into a flat plane by the elastic pressure thus exerted at the ends thereof.

Complete collapsibility of the easel is apparent 25 from the drawings.

A fourth form of the invention is shown in Figures 9 and 10. Sheet material 10 and cross members 11 and 13 are used therein. The easel comprises a Y-shaped means having as a part 30 thereof, a lower strip 58 and upper strips 59 and 60 which form a Y when spread. Strips 59 and 60 are relatively movable and are movable relatively to strip 58, the three being joined by a rivet 68.

35 Strip 59 may be permanently but movably fastened to upper cross member 13 by rivet 62 and strip 60 may be permanently but movably fastened to the same member 13 by rivet 63. Such fastenings do not interfere with rolling up the 40 device into a small space inasmuch as when disconnection is had in respect to strip 58, the arm strips 59 and 60 may be arranged parallel to cross member 13 and may be rolled up as is shown in Figure 17. The lower strip 58 is removably attached to cross arm 11 by means of rivet 21 engaging in an open-ended slot 64.

Firm positioning of strip 58 in slot 64 to obtain 45 a stretching effect is obtained by the elastic means now to be described. Strips 59 and 60, parallel to their length, have elongated slots 65 and 66 which are brought into registry with an aperture 67 in strip 58, the three strips being movably bound together by rivet 68 having a shank 69.

In each elongated slot 65 and 66, there is an 50 enlarged end, such as 71 and 72 whereby the head 70 of said rivet 68 may be withdrawn. Horizontally in respect to said placard, when in use, but diagonally in respect to the length of strips 59 and 60, and extending from the outermost corners of said strips are kerfs 73 and 74.

An elastic means 334 is disposed across kerfs 55 73 and 74 and exerts upon strips 59 and 60 a force tending to draw the short ends thereof together, the same force tending to elongate the three members vertically. The effect of such force is communicated to cross members 11 and 13, drawing sheet material 10 into a flat plane.

In this form of device, the strip 58 has attached thereto a leg forming member identical with that illustrated in the second form of the present invention herein discussed.

A fifth form of the invention is shown in Figures 11 and 12. The essential features of stretching the sheet 10 and providing a resiliency in respect to the support thereof are again present.

Expansive or stretching effect is obtained by having an easel of two members riveted together to conjointedly provide an easel of a length which must be compressed when attached to said sheet material 10. In such form of the device, reliance for expansive force is had in the tensile strength of the easel strips composing easel 414. 80

Easel 414 is fastened to cross strips 11 and 13 by the use of horizontal slots 75 and 76, engaging the usual rivets supplied in strips 11 and 13. 85 Easel 414 is composed of strips 77 and 78, the former, 77, serving partly to extend the sheet 10 and to provide a leg from the section 79 thereof. Strip 78 serves to expand the sheet 10 and partly as a stay 79a to maintain the lower 90 part 79 of strip 77 in its supporting angle.

Strip 77 is articulated at 80, the material therebeneath fitting into the curved end 81 of strip 78. Strips 77 and 78 are fastened together by a short strip 82 by rivets 83 and 84. Lateral movement of said upright members 77 and 78 is generally prevented by the engagement of end 81 of strip 78 against section 79 of strip 77, but is positively prevented by the use of a rubber band 434 which may be employed, and which, 100 when employed, serves to permit additional bending of strip 77 when the length of strips 77 and 78 greatly exceeds that of sheet material.

By removing elastic 434, bending section 79 back upon 77 and rotating strip 78, 180 degrees 105 about rivet 83, compactness is assured in the collapsed easel.

The sixth form of the invention is illustrated in Figures 13 and 14, such form operating upon a principle similar to that disclosed in Figures 11 and 12. Strips 85 and 86 intersect and also intersect strip 87. They are held together by rivet 88. Strip 85 may be permanently but movably fastened to cross member 13 by rivet 89 and strip 86 may be removably fastened to a protruding rivet 90 in cross member 13 by means of keyhole slot 91. 110

Strip 87 possesses a keyhole slot 92. By disconnecting strip 87 from rivet 88 and disengaging strip 86 from rivet 90, strips 85 and 86 may be 115 arranged in parallelism and disposed on cross member 13 preparatory to rolling the device into a compact bundle. The lower part of the device is a reproduction of the upper part merely inverted. 125

A unique feature of the present form of the invention is that strip 87 as shown in Figure 14, is a section of a single strip of material which may be bent into the form of an uncompleted triangle whereby its long section is a leg 93 furnishing support to the sheet 10. Its short section 94 serves as a cross stay to maintain leg 93 in a predetermined relationship to the sheet 10. Said section 94 has an angle bracket 95 articulated 130 therein with a keyhole slot 96 to engage cross member 11 upon rivet 21 therein.

Complete collapsibility of this framework is perfectly apparent.

The last form of the invention to be described is an adaptation of the Y-shaped support illustrated in Figure 9 utilizing the strength of the strip material of the easel when bowed to provide stretching means for sheet 10. Strips 98 and 99 intersect one another and intersect vertical strip 100. Rivet 101 joins the strips together with strip 99 further removed from the sheet 10. Strip 98 is permanently but movably fastened to cross member 13 by rivet 102 and strip 99 is removably fastened to cross member 13 by rivet 103 by the use of a keyhole slot 104. 135 140 145 150

Strip 100 has a keyhole slot 105 therein and is removably secured to cross member 11 by rivet 21. Said strip 100 forms one section of a triangularly shaped member, the rear section 106 of which 5 is a leg or supporting means for the sheet 10 and the lower section 107 of which forms a cross bar to maintain supporting strip 106 in a predetermined relationship with the placard.

Expansive effort is exerted upon cross members 10 11 and 13 by the strips 98, 99 and 100 which have a total extent exceeding the distance between rivets 102, 103 and 21. Strips 98, 99 and 100 are therefore forced into an arched or bowed position as shown in Figure 16 and their elasticity 15 maintains sheet material 10 in spaced position.

Collapsibility is assured by disengaging strip 100 from rivet 21 and strip 99 from rivet 103. Strips 98, 99 and 100 may be permanently attached to each other by rivet 101. The three 20 strips may be arranged in parallelism and as strip 99 is outwardly disposed in respect to strip 98, there is no interference from rivet 102.

As in preceding forms of the invention, strip 100 forms but a section of a triangular support, 25 the back section 106 of which serves as a leg.

Figure 17 is an elevation of any of the several forms of the invention showing the display device collapsed and rolled into the paper sheet 10. A rubber band binds the whole device into a compact package.

I claim:

1. An advertising device comprising a poster sheet, an easel therefor comprising strips extending from the corners at one end of said sheet in combination with another strip extending to the opposite end of said sheet, and means for forcing said corner engaging strips together to stretch said sheet longitudinally, all of said strips having their broad faces parallel to the faces of the poster sheet.

2. An advertising device comprising a poster sheet, an easel therefor comprising strips extending from the corners at one end of said sheet in combination with another strip extending to the opposite end of said sheet, and means for forcing said corner engaging strips longitudinally away from said end engaging strip, all of said strips having their broad faces parallel to the faces of the poster sheet.

3. An advertising device comprising a poster sheet, an easel therefor comprising strips extending from the corners at one end of said sheet in combination with another strip extending to the opposite end of said sheet, and means for reducing the angle between the outer ends of said corner engaging strips and forcing said end engaging strip longitudinally away from said corner engaging strips.
